FEEDING DEVICE FOR ROCK DRILLS

William A. Morrison, Easton, Pa., and George H. Fuehrer, Phillipsburg, N. J., assignors to Ingersoll-Rand Company, New York, N. Y., a corporation of New Jersey

Application April 12, 1940, Serial No. 329,210

10 Claims. (Cl. 121—9)

This invention relates to rock drilling mechanism, and more particularly to a feeding device for advancing a rock drill toward and retracting it from the work.

In a more specific sense, the invention relates to a feeding device for rock drills of the drifter type in which the rock drill is actuated along a guide member by a feed screw rotated by a fluid actuated rotary motor. In practice the guide member is attached to a supporting device, as for example a bar or frame and the rotary motor rotates the feed screw to advance the rock drill toward the work in accordance with the penetration of the working implement therewith.

In operations in which a group of rock drills actuated by rotary feeding motors are mounted on the same bar or frame it has been found that the combined forces of the feeding motors tend to thrust the supporting member away from the work. Even highly rigid supports are deflected or bent to some extent, and when some of the rock drills of a battery have completed their run of drilling the thrust of the mounting must be borne by the drilling mechanisms still in operation. This condition often forces the operating working implements so hard against the chuck parts of the rock drills that they tend to tilt within their housings and become worn excessively as a result.

It is accordingly an object of the invention to equip the feeding mechanism with a cushioning member that will yield to relieve excessive pressure against the chuck parts of the rock drill.

Another object is to automatically cut off the power to the feeding motor in the event that the pressure against the chuck parts of the rock drill becomes excessive.

Another object is to automatically effect resumption of feeding movement after the pressure on the chuck parts has been relieved.

Other objects will be in part obvious and in part pointed out hereinafter.

In the drawing accompanying this specification and in which similar reference numerals refer to similar parts,

Figure 1 is a longitudinal side view, partly broken away, of a rock drill, its guide member and a rotary feeding motor for actuating the rock drill along the guide member.

Figure 2 is a longitudinal view, partly broken away, of a rotary feeding motor and a fragmentary portion of a rock drill to which the feed screw of the motor is threadedly connected.

Figures 3, 4 and 5 are transverse views taken through Figure 2 on the lines 3—3, 4—4 and 5—5, respectively.

Referring more particularly to the drawing and at first to Figure 1, the drilling mechanism designated in its entirety by 20, comprises a rock drill 21 mounted upon a guide member in the form of a shell 22 and at the rear end of the shell 22 is a feeding motor 23 for actuating the rock drill 21 longitudinally of the shell through the instrumentality of a feed screw 24.

The shell 22 may be of a well known type having a cone 18 for cooperation with a suitable clamping device (not shown) whereby the drilling mechanism may be secured to a stationary mounting. In the opposed inner surfaces of the shell are longitudinally extending grooves 25 to receive, slidably, ribs 26 extending along opposite sides of the rock drill 21.

The rock drill 21 likewise may be of a conventional type comprising a cylinder 27 and front and back heads 28 and 29, respectively, which may be secured to the cylinder in any well known manner. The cylinder and heads 28 and 29 constitute the casing parts of the rock drill and within the front head 28 is a chuck 30 to receive the shank end 31 of a drill steel 32 having lugs 33 to slidably interlock with the chuck.

The chuck 30 is of the rotatable type to which rotary movement may be transmitted by suitable mechanism (not shown) incorporated in the rock drill in a well known manner, and in the chuck 30 is a chuck bushing 34, the front end of which acts as an abutment for the lugs 33 to limit the distance which the working implement may extend into the rock drill.

The cylinder 27 of the rock drill carries a lug 35 located between the ribs 26, and in the lug 35 is a feed nut 36 that is in threaded engagement with the feed screw 24 and locked securely in position by a nut 37 seating against the end of the cylinder 27.

The motor 23, which is attached to the rear end of the shell 22 by standards 38, is of the fluid actuated rotary vane type. It comprises a casing 39 having lugs 40 to receive the standards 38 and is bored to provide a chamber 41 for the accommodation of a piston or rotor 42. The rotor 42 is disposed eccentrically within the chamber 41 and is provided with a plurality of radial slots 43 containing vanes 44 against which pressure fluid acts for rotating the rotor.

The motor 23 is of the reversible type and the direction of rotation thereof is controlled by a valve 45 rotatable in a valve chamber 46 adjacent the chamber 41. The valve 45 has a bore 47 and a port 48 opening into the bore 47 and adapted to register with passages 49 and 50 leading to oppo-

site sides of the point of minimum clearance between the wall of the chamber 41 and the outer surface of the rotor.

In the periphery of the valve 45 is a partly annular groove 51 to register selectively with the passages 49 and 50 for placing said passages in communication with a free exhaust port 52 leading from the valve chamber 46 to the atmosphere. The valve 45 is of less length than the valve chamber 46 and is held in one end thereof by a nut 53 threaded on a projecting stem 54 of the valve for holding a lever 55 thereon. The chamber 41 is also provided with free exhaust ports 56 and 57 arranged on the opposite sides of the plane of maximum clearance between the wall of the chamber 41 and the periphery of the rotor 42.

The rotor 42 is mounted upon a shaft 58 journaled in the rear and front heads 59 and 60 of the motor casing and is secured to the rotor by a key 61. The shaft 58 extends forwardly of the head 60 and carries a sun pinion 62 that meshes with planet pinions 63 meshing with an internal gear or, as illustrated, teeth 64 on the inner surface of a casing 65 seating against the front end of the head 60. The pinions 63 are mounted upon spindles 66 seated in a carrier 67 rotatable in the casing 65.

On the front end of the carrier is a skirt 68 which is journaled in a bushing 69 in the casing 65, and on the inner surface of the skirt 68 are longitudinally extending ribs 70 that mesh with ribs 71 on the periphery of a sleeve 72 keyed to the rearward end of the feed screw 24 and held thereon by a nut 73. The sleeve 72 is slidable longitudinally of the carrier 67 as is, of course, also the feed screw 24 of which the front end 74 is journaled, slidably, in a bearing 75 carried by the shell 22.

The rear end of the feed screw adjacent the sleeve 72 lies in a bushing 76 arranged in a boss 77 in the casing 65 and having an external flange 78 that seats against the front end of the boss 77. The boss 77 projects into a head 79 arranged at the front end of the casing 65 and cooperates with the head 79 to define a pressure chamber 80 in which is arranged a piston 81 that serves to oppose the rearward movement of the feed screw with respect to the motor.

The piston 81 encircles the rearward end of the feed screw 24. It is slidable relatively to the feed screw and is slidably interlocked with the head 79 by a key 82 seated in a reduced forward extension 83 of the piston. The extension 83 may, as shown, protrude from the front end of the head 79 and has an internal shoulder 84 to abut the rearward surface 85 of a collar 86 carried by the feed screw. A sealing ring 87 is arranged in the periphery of the piston 81 and a sealing ring 88 is preferably arranged in the flange 78 to seat against the inner surface of the piston 81 for preventing leakage of pressure fluid from the chamber 80 along the boss 77. A vent 89 in the head 79 communicates the front end of the chamber 80 with the atmosphere.

The pressure fluid to which the piston 81 is subjected is conveyed into the pressure chamber 80 by a passage 90 in the casing 65 and is supplied to the passage 90 by a conduit 91. As a preferred arrangement, the pressure fluid used for operating the motor also passes through the pressure chamber 80. To this end a passage 92 leads from the pressure chamber 80 from a point intermediate the ends of said chamber through

the head 79, the casing 65 and the motor casing and its heads to the front end of the valve chamber 46 forwardly of the valve 45 so that the bore 47 will be in constant communication with the passage 92.

The passage 92 is so located with respect to the pressure chamber 80 that it will be fully uncovered when the piston 81 is in its foremost limiting position, and a groove 93 of gradually diminishing flow area leads rearwardly along the wall of the pressure chamber 80 from the passage 92 to a point intermediate the passage 92 and the rear end of the pressure chamber 80. In this way, when the piston 81 is thrust rearwardly across the passage 92 the flow of pressure fluid from the pressure chamber 80 to the passage 92 will be gradually cut off.

During the normal operation of the drilling mechanism and with the valve 45 in a position to admit pressure fluid into the motor to cause feeding movement of the feed screw 24, the pressure fluid flowing through the pressure chamber 80 will hold the piston 81 in the front end of the pressure chamber 80 and the shoulder 84 against the collar 86 of the feed screw. The motor will then rotate the feed screw to maintain the percussive element of the rock drill in the correct striking relationship with the drill steel 32 and a full supply of pressure fluid passes from the pressure chamber 80 through the passage 92 and associated passages to the motor.

The parts will remain in the positions described as long as the working implement and the chuck parts are subjected only to normal feeding pressure. In the event, however, that the pressure against the working implement becomes excessive, as when the mounting supporting the drilling mechanism shifts to a position in which a portion of its weight and that of the drilling mechanisms leans against the drill steels, the feed screw will be moved rearwardly against the force of the pressure fluid acting against the piston 81 and in that way the pressure against the chuck parts will be relieved.

This rearward movement of the feed screw 45 will cause the piston 81 to move into the plane of the passage 92 and thus partially cut off the flow of pressure fluid to the motor 23 and thereby reduce the power of the motor. Should the pressure of the drilling mechanism and its mounting against the working implement be unduly great the piston 81 will be moved still further rearwardly until it completely overlies the passage 92 and cuts off the flow of pressure fluid to the motor altogether.

The motor will then be idle and with the rock drill 21 continuing to operate the working implement 32 will be driven into the rock and thereby provide additional clearance. Meanwhile the pressure acting against the piston 81 will urge the feed screw forwardly, and when the piston again uncovers the groove 93 pressure fluid will be admitted to the motor 23 which will then be set in operation and again rotate the feed screw 24 for feeding the rock drill toward the work. This feeding movement of the piston 81 may continue independently of the motor until all the parts are restored to a position in which little or none of the weight of the drilling mechanisms and their mounting leans against the working implement, and the piston 81 will then be in position to permit the flow of a full supply of pressure fluid to the motor for rotating it.

After the working implement has been driven into the rock to the limit of its extent, or when

a drill hole has been completed, the valve 45 is rotated to its other extreme position for reversing the motor. The feed screw will then be turned in an opposite hand direction for retracting the rock drill to its starting position.

We claim:

1. In a feeding device, the combination of a guide member and a rock drill slidable thereon, a rotary feeding motor for the rock drill, a feed screw slidable longitudinally in the guide member threadedly engaging the rock drill, and being slidably interlocked with the motor, and means subjected to pressure fluid for cushioning the endwise movement of the feed screw with respect to the motor.

2. In a feeding device, the combination of a guide member and a rock drill slidable thereon, a feed screw slidable longitudinally of the guide member and being operatively connected to the rock drill, a motor for rotating the feed screw, transmission means forming a slidable connection between the motor and the feed screw, and means subjected to the pressure fluid flowing to the motor for cushioning the thrust of the feed screw toward the motor.

3. In a feeding device, the combination of a guide member and a rock drill slidable thereon, a rotary feeding motor for the rock drill attached to the guide member, a feed screw slidable longitudinally in the guide member threadedly engaging the rock drill, means slidably interlocking the feed screw with the motor, and means on the feed screw subjected to pressure fluid for cushioning the endwise movement of the feed screw.

4. In a feeding device, the combination of a guide member and a rock drill slidable thereon, a rotary feeding motor for the rock drill having a casing attached to the guide member, a feed screw slidable longitudinally in the guide member and the casing and being threadedly connected to the rock drill, means to slidably interlock the feed screw to the motor, a pressure chamber in the casing, and a piston in the pressure chamber subjected to pressure fluid to cushion the endwise movement of the feed screw toward the motor.

5. In a feeding device, the combination of a guide member and a rock drill slidable thereon, a rotary feeding motor for the rock drill having a casing attached to the rear end of the guide member, a feed screw slidable longitudinally in the guide member and the casing and being threadedly connected to the rock drill, splined members on the feed screw and the motor slidably interlocked with each other to transmit the rotary movement of the motor to the feed screw, and means controlling the flow of pressure fluid to the motor and being subjected to pressure fluid for cushioning the rearward movement of the feed screw.

6. In a feeding device, the combination of a guide member and a rock drill slidable thereon, a fluid actuated rotary feeding motor for the rock drill, a feed screw operatively connected with the motor and the rock drill, reciprocatory valve means for controlling the flow of pressure fluid to the motor, and being subjected to pressure fluid for moving said valve means in one direction, and means on the feed screw for actuating said valve means in the opposite direction.

7. In a feeding device, the combination of a guide member and a rock drill slidable thereon, a fluid actuated rotary feeding motor for the rock drill, a feed screw operatively connected with the motor and the rock drill and being slidable longitudinally of the motor, and means actuated by the feed screw upon endwise movement thereof for controlling the flow of pressure fluid to the motor.

20 8. In a feeding device, the combination of a guide member and a rock drill slidable thereon, a fluid actuated rotary feeding motor for the rock drill having a casing attached to the guide member, a feed screw operatively connected with the motor and the rock drill and being slidable longitudinally of the motor, and means in the casing subjected to pressure fluid for cushioning the endwise movement of the feed screw and being actuated by the feed screw to control the flow of pressure fluid to the motor.

25 9. In a feeding device, the combination of a guide member and a rock drill slidable thereon, a fluid actuated rotary feeding motor for the rock drill having a casing attached to the guide member, a feed screw operatively connected with the motor and the rock drill and being slidable longitudinally of the motor, a pressure chamber in the casing, a supply passage leading from the pressure chamber to the motor, and a piston in the pressure chamber subjected to pressure fluid for cushioning the rearward movement of the feed screw and being actuated by the feed screw to control the supply passage.

30 10. In a feeding device, the combination of a guide member and a rock drill slidable thereon, a fluid actuated rotary feeding motor for the rock drill having a casing attached to the guide member, a feed screw operatively connected with the motor and the rock drill and being slidable longitudinally of the motor, a pressure chamber in the casing, a supply passage leading from the pressure chamber to the motor, a shoulder on the feed screw, and a piston in the pressure chamber slidable on the feed screw to engage the shoulder for cushioning the rearward movement of the feed screw and being actuated by the feed screw to control the supply passage.
